UNITED STATES PATENT OFFICE

HENRY G. KUCK AND THEODORE J. ABELE, OF PEORIA, ILLINOIS, ASSIGNEES TO
STUBER & KUCK CO., OF PEORIA, ILLINOIS, A CORPORATION OF ILLINOIS

COVERS FOR RECEPTACLES

Application filed December 29, 1930. Serial No. 505,347.

This invention relates to receptacle covers or closures provided with cover glasses. More particularly the invention has to do with an improved construction in a closure 5 of the type named by which a broken cover glass may be easily and quickly replaced.

An object of our invention is the provision of a cover or closure of two parts adapted to telescope one into the other, said parts being 10 identical in form and size, the glass being held between the two.

Another object lies in providing two identical rings which together form a closure for a receptacle, the same being telescoped 15 and adapted to hold between them the cover glass, said rings being separable for the purpose of replacing a broken glass, removable means being employed for securing the rings in connected relation.

20 The appended drawing is provided in order to make our invention fully understood. Figure 1 is a vertical section of a portion of a receptacle showing the cover or closure of our invention applied thereto. Figure 2 is an enlarged vertical section of portions of 25 the lid or cover and the receptacle to which the same is applied. Figure 3 shows portions of two rings in perspective. Figure 4 is a section of parts of the two rings shown in the earlier figures and means for securing them 30 relatively, and Figure 5 shows in perspective parts of the receptacle and our invention applied thereto.

The body of the receptacle is denoted at 1. 35 A cover is provided for said receptacle identified in general by the character 2. It has the form of a ring and includes a flange 3 to engage over the receptacle's top and, within the central opening thereof the ring has an 40 inwardly extending flange or lip 4 terminating an inner depending wall 5. Thus formed the cover has the central opening 6, said cover constituting what may be termed a primary closure for the receptacle. It is re- 45 movable and receives a secondary cover or closure which may preferably be hinged thereto. This said secondary closure, therefore, is that portion through which the goods in the receptacle may be inspected, being pro- 50 vided with a cover-glass and may be raised

for dispensing the goods protected thereby.

Such secondary closure comprises a pair of rings of identical form and size, each comprising in this instance a cylindrically formed wall portion 7, 8 and a flange portion 9, 10, respectively, lying in planes at right angles to said wall portions as best shown in Figures 2 and 3, and the said cylindrically formed walls may terminate each in an outwardly turned flange 11 at its lower free edge.

A glass cover-plate is represented at 12 and is placed within the upper of the two rings, covering the central opening 13 thereof, and when so placed is followed by the ring 8, the margin of the glass being thus enclosed between the two flanges 9, 10. Holes 14 are provided in the walls 7, 8 in register for the reception of easily removable members 15 which, for example, may correspond to the well known paper fastener, or like device, by which the rings may be maintained in positive connected relation.

Although the drawing indicates the rings 7-9 and 8-10 as being of heavy gauge for purposes of better showing yet, as is well known, the "tin" from which metal ware is constructed is really of quite light gauge and, therefore, although the said rings are identical in size one may be telescoped into the other, the flange 7 of the outer ring readily "giving" as the inner ring is inserted to enclose the cover-glass 12, Figures 2 and 5, the flanges 9, 10 being spaced in accordance with the thickness of said glass.

The flange 11 of the inner ring 8-10 finds an abutment upon the flange 4 of the wall 5 of the primary closure-ring 2, and a convenient grip 16 may be secured to the flange 9, while a hinge 16' may be fixed to the latter and to said primary closure, see Figure 1, in addition to which there may be erected on the said primary closure a stop 17 to support the lid or cover 7, 8, 12 and when raised during dispensing periods.

The rings 7, 8 are identical as already stated being made from the same set of dies thus saving in cost of manufacture besides providing for an exceedingly snug fit, in addition to which the rings are thus provided with the same type and width of flanges 9, 10.

and furnishing wide marginal embracing portions for the glass, which portions serve to cushion the glass and assist largely in preventing breakage of the glass when the lid 5 or cover is dropped to its closed position through accident.

The primary cover 2 due to its form provides the low hanging flange 4 within the opening 6 forming a well into which the secondary cover enters with its top substantially flush with the top of said primary cover thus making for an extremely neat appearance besides reducing the bulk of the whole structure which is an advantage when considering 10 the matter of storage in a small space, and in shipping.

We claim:

1. A cover for a receptacle including a pair of rings of formed sheet metal having 20 cylindrically curved walls and identical form and size arranged to nest one within the other, each including a flange, and a cover-plate held in position between said flanges, said walls adapted to be held in connected relation by their frictional engagement.
2. A cover for a receptacle including a pair of rings each comprising a substantially cylindrically curved wall and an integral flange disposed substantially at right angles thereto, 30 said rings being identical in size and form adapted to nest one in the other and separable one from the other, and a cover-plate held between the said flanges.
3. The invention according to claim 2 together with means to secure the rings in their nested relation.
4. A cover for a receptacle including a primary cover portion comprising a ring or annulus to rest upon the side wall of the receptacle including an inner annular substantially cylindrical wall depending into the receptacle below the top edge thereof and terminating inwardly at its lower extremity in an inwardly formed flange forming a support, and 40 a secondary cover comprising a pair of rings of identical form and size each including a substantially cylindrically curved wall adapted to nest one within the other and held frictionally in engagement, and separable, one 45 of them resting upon the said flange of said primary cover, and each including an inwardly extending flange one substantially paralleling the other, and a cover glass disposed between the flanges, the said secondary 50 cover in overall height being substantially equal to the height of the cylindrical wall of the said primary cover and lying below the outer margin of the said primary cover.
5. A cover for receptacles including in its 55 construction a pair of rings each comprising a substantially cylindrically curved wall and a flange extending inwardly therefrom substantially at right angles thereto, said rings being of identical size and form, the said 60 walls adapted to telescope each other, and 65

separable, the said flanges adapted to lie in spaced relation for receiving a cover glass between them.

In testimony whereof we affix our signatures.

HENRY G. KUCK.
THEODORE J. ABELE.
